UNITED STATES PATENT OFFICE.

JOHN JAMES AURINGER, OF COHOES, NEW YORK.

BATTERY-ELECTRODE.

1,081,277.

Specification of Letters Patent.

Patented Dec. 9, 1913.

Application filed January 17, 1913. Serial No. 742,571.

To all whom it may concern:

Be it known that I, JOHN JAMES AURINGER, a citizen of the United States, residing in the city of Cohoes, county of Albany, 5 and State of New York, have invented a certain new and useful Battery-Electrode, of which the following is a specification.

The object of the present invention is to produce an electrode for electric batteries, 10 either of the wet or dry type, in which the E. M. F. will be increased and the internal resistance reduced. This and further objects will more fully appear from the following specification and accompanying 15 drawing, considered together or separately.

In the drawings, Figure 1 is a plan view of an electrode embodying the invention; Fig. 2 is a side elevation of the same; Fig. 3 is a plan view of a modification; Fig. 4 is a 20 side elevation of the same; Fig. 5 is a plan view of another modification; Fig. 6 is a side elevation of the same; and Fig. 7 is a bottom view of the same.

In all views, like parts are designated by 25 the same reference characters.

Figs. 1 and 2 illustrate an electrode particularly applicable for dry batteries, *i. e.*—cells using a non-liquid electrolyte. The electrode is made of strips or layers of gas 30 carbon and retort carbon. The strips *a*, *a*, are of gas carbon. The strips *b* are of retort carbon. The strips of gas carbon and retort carbon are alternately arranged as shown. They are preferably secured together by baking. A bolt *c*, with a nut *d* is inserted in the electrode and forms a binding post.

In the structure illustrated in Figs. 3 and 4, the layers of gas carbon and retort carbon 40 are laterally arranged. This form of electrode is particularly applicable for use with wet batteries, *i. e.*, cells with a liquid electrolyte.

Figs. 5, 6 and 7, illustrate a modification 45 of the invention in which one of the two kinds of carbon is in the form of a central rod *e*, with peripheral grooves in which are embedded strips *f*, of a different kind of carbon. The strips are preferably of the 50 circular cross-section illustrated, so that the surface area of the electrode is augmented. The strips may be of either gas carbon or

retort carbon, the rod in either case being of a different kind of carbon from the strips.

The electrode may be permanently welded 55 together by baking.

My improved electrode possesses much less internal resistance than an electrode made of solid carbon. With equal amounts of carbon in the electrode, my improved 60 electrode gives greater E. M. F. than an electrode of one kind of carbon. The gas carbon which I employ differs from the retort carbon, in that it may contain some tar or pitch. The retort carbon may be made 65 of powdered or flake carbon. The electrode, when utilized in a wet battery, will possess advantages over an electrode formed of but one kind of carbon, due to reaction of the chemicals at different depths, caused by 70 different specific gravities.

Gas carbon is the product commonly formed in gas-retorts by distillation of hydrocarbons and contains a greater or less percentage of tar. Retort carbon is likewise a product formed in gas-retorts by distillation of hydrocarbons but which has been sufficiently heated to become partially, more or less, graphitized. The gas carbon has greater conductivity than retort carbon and 75 is employed because of its conductivity; and the retort carbon is used because of its properties to reduce resistance of hydration when employed in a battery having an electrolyte.

In accordance with the provisions of the 80 patent statutes, I have described the principle of my invention, together with the apparatus which I now consider to represent the best embodiment thereof, but I desire to have it understood that the apparatus shown 85 is merely illustrative, and that the invention may be carried out in other ways.

Having now described my invention, what I claim as new and desire to secure by Letters Patent, is:—

1. An electrolytic electrode formed of a body of gas carbon and a separate exposed body of retort carbon bonded to the gas carbon.
2. An electrode formed of gas carbon and an exposed surface of flake retort carbon.
3. An electrode formed of gas carbon and an exposed surface of flake retort carbon bonded to the gas carbon.

- 22
- 4. An electrode having a surface formed of alternate succeeding areas of carbon, one such area having greater conductivity than the other.
  - 5. An electrode formed of gas carbon and retort carbon, having a center rod of carbon, with peripheral longitudinal grooves, and strips of carbon embedded in the grooves,

the rod and strips being of different kinds of carbon.

This specification signed and witnessed this fourth day of January, 1913.

JOHN JAMES AURINGER.
